UNITED STATES PATENT OFFICE

GOLIAT DAVISON, OF ST. LOUIS, MISSOURI, ASSIGNOR OF ONE-THIRD TO JOHN SPEROULIAS AND ONE-THIRD TO GEORGE ABATGIS, BOTH OF ST. LOUIS, MISSOURI

HANGER FOR FUR SCARFS AND THE LIKE

Application filed May 22, 1931. Serial No. 539,156.

This invention relates to hangers for fur scarfs and the like.

An object of the invention is to provide an improved hanger for use in connection with fur scarfs and the like comprising a spring clasp attached to one end portion of the scarf and adapted to be adjusted to engage appropriately shaped supports in order to hang the scarfs from the support; 10 in combination with a pivoted hanger element in connection with the spring clasp constructed and arranged to be optionally engaged with supports of different types with which the spring clasp cannot be 15 engaged.

Another object of the invention is to provide means for supporting a receptacle, such as a compact case or the like, in connection with a fur scarf and utilize this receptacle 20 as a cover and protector for a hanger member pivotally connected therewith between the receptacle and an adjacent portion of the scarf.

Other objects will be apparent from the 25 following description of the invention, reference being made to the accompanying drawing, in which—

Fig. 1 is a side elevation showing my improved hanger attached to a fur scarf.

30 Fig. 2 is a rear side view of the invention, the case being open.

Fig. 3 is a sectional view approximately on the line 3—3 of Fig. 1, the compact case being removed.

35 A portion of a fur scarf 1 is conventionally shown. This scarf has in rigid connection with the inner side thereof a jaw 2 of a spring clasp. The cooperating jaw 3 of the spring clasp has ears 4 extending along 40 side of the ears 5 in connection with the jaw 2 and pivotally connected therewith by a hinge pin 6. A spring is coiled about the hinge pin 6 and has its ends 7 bearing against the adjacent surfaces of the jaws

45 2 and 3, respectively. The power and energy of this spring is utilized to press together the curved gripping ends 8 of the spring clasp. The ends 8 of the spring clasp terminate inwardly a short distance from the end 50 of the fur scarf, so that said ends do not

protrude beyond the end of the fur scarf but are entirely concealed thereby when the scarf is worn.

A clasp of this type may be manipulated and operated so as to clasp on substantially flat supports or clasp about supports of comparatively small diameter. 55

Supports for engagement by the clasp ends 8 are not always accessible and available in places where it is desired to hang the fur scarf. I provide for this contingency by embodying in the present invention a hanger that is normally concealed but which may be moved to extended position so as to project far beyond the clasp ends 8 and beyond the end of the scarf. This hanger device is constructed and designed so that it may be moved to this extended position and then engaged with the usual or conventional 60 hooks or nails or rod supports. 65

In the embodiment shown, this extendible hanger comprises a rod or wire element shaped to provide a stem 9 rolled at one end to form an eyelet 10 that is engaged on a pivot 11 rigid with the jaw 3; the opposite end of the element 9 being curved to provide a hook 12. This hook is formed as to configuration and size, so that it is easily engageable with hanger hooks, nails, pegs and rods. Thus, the scarf may be suspended 70 from any of these usually accessible elements with which the spring clasp can not possibly or easily be engaged. 75

A wall member 13 is attached to the pivot 11 and to a number of spacer and abutment pins 14 and 15 that project from the clasp jaw 3. The wall 13 is thus supported at a distance from the jaw 3 to provide a space 16 into and from which the hook hanger device may readily be moved to the position indicated in Fig. 3 of the drawing. When the hook hanger device is in its unoperated position between the jaw 3 and the wall 13, the entire hook hanger device is covered and protected by the wall 13, so that it is impossible for said hook hanger device to become engaged or entangled with the clothing of the wearer of the fur scarf. In this unoperated position of the hook hanger device, it rests against the pin 14. Accordingly, 80 85 90 95 100

this pin 14 serves a double function of supporting the wall 13 in spaced relationship from the wall 3 and also as a stop for the hook hanger device when the hook hanger device is moved to the unoperated position shown by broken lines in Fig. 3. The pin 15 serves the function of stopping or limiting extent of turning movement of the hook hanger device about the pivot 11 when said device is moved to its extended position and also serves to cooperate with the pins 11 and 14 to support the wall 13.

The wall 13 may also be used as the bottom wall of a compact case, so that said wall 13 is required to perform the two functions of protecting and covering the hook hanger and of providing a bottom wall for a case. The side wall 17 of the case is pressed or bent so as to extend outwardly at right angles from the wall 13 and thereby provide a case enclosure to receive and contain a toilet device, such as a powder puff 18.

The closure for the case comprises a wall 19 having in connection therewith a marginal wall 20 adapted to telescope about the marginal portion of the wall 17 so as to form a complete enclosure. A bead 21 on the wall 20 is adapted to engage an indentation 22 formed on the wall 17 so as to hold the lid in closed position. The walls 17 and 20 are preferably of resilient metal, so that it is easy to latch and unlatch the lid in this manner.

The inner side of the wall 19 may be used as a support for a mirror 23. This mirror is covered and enclosed when the lid is closed but is open and exposed to view when the lid is open.

The hook 12 may be formed with a protuberance 24 which will extend beyond the inner end of the case just described, so that said protuberance may be easily engaged by the finger and constitute means for swinging the hook hanger device from its unoperated position to its extended position. This protuberance is needed because the peripheral portion of the hook 12 is smooth and is entirely covered by the wall 13.

It is now clear that my invention obtains all of its intended objects and purposes very efficiently and satisfactorily. The hook hanger device may be used independently of the toilet case and in connection with numerous articles other than fur scarfs. I contemplate such variations in construction and arrangement of the device as may be desirable to adapt it for numerous uses, and I also contemplate the application of the device to use in connection with various articles.

I claim:

1. A device of the character described comprising a supporting pivot, means holding said pivot in connection with an article to be suspended, a hanger member having

one end pivoted on for swinging movements about said pivot and having a hook on the opposite end, and a wall attached to said pivot and arranged to cover said hanger member when said hanger member is in an unoperated position and to expose said hook when said hanger is in its operated position.

2. A device of the character described comprising a pair of spaced walls attached to an article to be suspended, a hanger member having one end pivoted for turning movements between said walls, said hanger member being swingable from position entirely between said walls to position in which one end projects beyond said walls, and a hook in connection with said last named end of said hanger member.

3. A device of the character described comprising two wall members attached together in spaced relationship to provide an intervening space and supported by an article to be suspended, and a hook hanger having one end pivoted between said wall members and being swingable to position entirely between said wall members and to position in which said hook hanger projects beyond said wall member and beyond the end of the article to be suspended.

4. A device of the character described comprising two wall members in rigid connection with each other and with an article to be suspended and being supported by an intervening space, and a hanger member having a hook on one end and having the opposite end pivoted between said wall members, said hanger member being swingable to position entirely between said wall members when not in use and also being movable to position to extend beyond said wall members when it is desired to use said hook.

5. A device of the character described comprising two wall members in rigid connection with each other and with an article to be suspended and being supported by an intervening space, a hanger member having a hook on one end and having the opposite end pivoted between said wall members, said hanger member being movable to position entirely between said wall members when not in use and also being movable to position to extend beyond said wall members when it is desired to use said hook, and means in connection with one of said wall members forming an enclosing case.

6. A hanger for an article to be suspended comprising a pair of spaced walls attached to said article, and a hanger member mounted in the space between said walls and swingable from position in which said hanger member is within the space between said walls to position in which one end of said hanger member projects beyond the ends of said walls and beyond the article to be suspended.

7. A hanger for an article to be suspended comprising a pair of spaced walls attached to said article, a hanger member mounted in the space between said walls and swingable from position in which said hanger member is within the space between said walls to position in which one end of said hanger member projects beyond the ends of said walls and beyond the article to be suspended, and means connecting said hanger member with and preventing said hanger member from becoming detached from said walls.

8. A hanger for an article to be suspended comprising a pair of spaced walls attached to said article, a hanger member mounted in the space between said walls and swingable from position in which said hanger member is within the space between said walls to position in which one end of said hanger member projects beyond the ends of said walls and beyond the article to be suspended, means connecting said hanger member with and preventing said hanger member from becoming detached from said walls, and elements limiting extent of movement of said hanger member to position in said space between said walls and to said extended position.

9. The combination with an article to be suspended, of a hanger member for said article comprising a pair of spaced walls in connection with one end portion of said article, a hanger member, an element holding said hanger member in connection with said walls and permitting swinging movement of said hanger member to position between said walls and to position in which said hanger member extends beyond said walls and said article, and means preventing swinging movement of said hanger member beyond its intended positions between said walls and extended beyond said walls as aforesaid.

10. The combination with an article to be suspended, of a hanger member pivotally connected with one end portion of said article and being swingable from position underlying said article to position in which said hanger member extends beyond the adjacent end of said article, walls supported in position to support said hanger member between them when said hanger member underlies said article, and a projection in connection with said hanger member for engagement to withdraw said hanger member from between said walls.

11. The combination with an article to be suspended, of a pair of walls in connection with one end of said article, and a hanger member swingable from between said walls to position in which said hanger member underlies said article and to position in which said hanger member projects beyond the end of said article.

GOLIAT DAVISON.
